DESIGN FOR A COMBINED TEA URN AND STAND

Vilhelm Hingelberg, Aarhus, Denmark

Application December 10, 1946, Serial No. 135,388

Term of patent 14 years

(Cl. D44—25)

all whom it may concern:

Be it known that I, Vilhelm Hingelberg, a citizen of Denmark, residing in Aarhus, Denmark, have invented a new, original, and ornamental Design for a Combined Tea Urn and Stand, of which the following is a specification, reference being had to the accompanying drawing, forming a part thereof, in which the single figure represents a perspective view of the combined tea urn and stand showing my new design. The body of the urn is symmetrical and a view from the opposite side is identical with that shown in the drawing.

I claim:

The ornamental design for a combined tea urn and stand, as shown and described.

VILHELM HINGELBERG.
